UNITED STATES PATENT OFFICE.

NATHANIEL L. HATHORN, OF ALEXANDRIA, LOUISIANA.

PLOW-SHIELD.

SPECIFICATION forming part of Letters Patent No. 773,074, dated October 25, 1904.

Application filed July 11, 1904. Serial No. 216,085. (No model.)

To all whom it may concern:

Be it known that I, NATHANIEL L. HATHORN, a citizen of the United States, residing at Alexandria, in Rapides parish and State of Louisiana, have invented certain new and useful Improvements in Plow-Shields; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to new and useful improvements in attachments for plows; and the object of the invention is to produce a shield which may be easily and quickly applied to an ordinary plow upon the landside thereof to prevent wear of the latter; and it consists of a plate having a longitudinal flange which is bent to engage over the bottom of the landside and provided with an integral hook upon its upper edge for engagement over the upper edge of the horizontal portion of the landside, the forward end of said shield being beveled to a sharp curved edge.

The invention consists, further, in various details of construction and combinations and arrangements of parts, as will be hereinafter fully described and then specifically defined in the appended claim.

My invention is illustrated in the accompanying drawings, which, with the letters of reference marked thereon, form a part of this application, and in which drawings—

Figure 1 is a side elevation of an ordinary plow, showing my attachment applied thereto. Fig. 2 is a section view on line 2-2 of Fig. 1. Fig. 3 is an enlarged detail perspective view of the shield or attachment, and Fig. 4 is a perspective view of the shield.

Reference now being had to the details of the drawings by letter, A designates a plow-beam provided with handles A' and a plow-stock B with plow B'.

D designates my improved shield or attachment, which may be of any suitable metal and of sufficient thickness to give strength and rigidity to the same, and a portion of the lower edge of said shield is bent upon itself, as at

D', and is adapted to engage a portion of the bottom of the landside E, while the forward edge of said shield is beveled, as at d. An integral hook F projects from the shield near its forward end and from the upper edge thereof and is bent preferably in the shape illustrated in the drawings for the purpose of engaging over the upper horizontal edge of the landside of the plow, as illustrated in Fig. 1 of the drawings. When the hook F is thus engaged, the bent portion D' should engage the bottom of the landside in the manner shown, after which said shield may be fastened to the landside either by means of a bolt H passing through the landside and the shield, as shown in Fig. 2 of the drawings, said bolt co-operating with a winged nut K, which bears against the wall of the shield for the purpose of clamping the latter tightly against the landside, or by means of a clamp in case the landside of the plow is not perforated for the reception of a bolt. It will be observed that the shield has a slot N transversely formed therein and through which a bolt may pass, thus providing means for a slight adjustment of the shield.

By the provision of an attachment as shown and described it will be observed that a simple and efficient device is provided for ready attachment to any ordinary plow for the purpose of rendering a plow the landside of which has become weakened through usage or wear useful, as the attachment, securely held to the plow in the manner shown, will render the landside rigid and prevent the same from further wear, and the attachment may also be applied to new plows for the purpose of preventing unnecessary wear.

While I have shown a particular detailed construction of device illustrating my invention, it will be understood that I may vary the same, if desired, as to details without in any way departing from the spirit of the invention.

Having thus fully described my invention, what I claim as new, and desire to secure by Letters Patent, is—

In combination with the landside of a plow, a shield having a portion of the lower edge thereof bent to form a flange which is designed

to engage under the bottom of the landside of the plow, the portion of the lower edge of said shield intermediate said flange and the forward upper edge being beveled, an integral hook projecting from the upper edge of said shield and adapted to engage over a horizontal portion of the landside, and a bolt passing through the landside and the slot in said

shield, and a winged nut for fastening the shield to the plow, as set forth.

In testimony whereof I hereunto affix my signature in presence of two witnesses.

NATHANIEL L. HATHORN.
